UNITED STATES PATENT OFFICE.

GEORGE L. ESTES, OF OKLAHOMA CITY, OKLAHOMA.

DESIGN FOR A TRAFFIC-SIGNAL CASING.

Application filed July 3, 1925. Serial No. 13,990. Term of patent 3½ years.

To all whom it may concern:

Be it known that I, GEORGE L. ESTES, a citizen of the United States, residing at Oklahoma City, Oklahoma County, Oklahoma, have invented a new, original, and ornamental Design for Traffic-Signal Casing, of which the following is a specification, reference being had to the accompanying drawing, forming a part thereof.

In the drawing—

Figure 1 is a perspective view of a traffic signal casing, showing my new design; and Figure 2 is a plan view of the same.

I claim:

The ornamental design for a traffic signal casing, as shown.

GEORGE L. ESTES.
